[57] CLAIM

The ornamental design for a stall partition for stall barns, as shown and described.

DESCRIPTION

FIG. 1 is a left side elevational view of a stall partition for stall barns showing my new design, the right side being a mirror image of the left side shown;

FIG. 2 is a front elevational view thereof;

FIG. 3 is a rear elevational view thereof;

FIG. 4 is a left side elevational view of the front portion thereof, the right side being a mirror image of the left side shown;

FIG. 5 is a front elevational view of FIG. 4;

FIG. 6 is a rear elevational view of FIG. 4;

FIG. 7 is a left side elevational view of the rear portion thereof, the right side being a mirror image of the left side shown;

FIG. 8 is a front elevational view of FIG. 7; and

FIG. 9 is a rear elevational view of FIG. 7.
